United States Patent Office

Des. 209,148
Patented Nov. 7, 1967

209,148

WORK DESK FOR A TELEPHONE OPERATOR

Francis C. Kegel, Tonawanda, N.Y., assignor to Barrett-Kegel Corporation, Franklinville, N.Y., a corporation of New York

Filed Oct. 11, 1966, Ser. No. 4,229

Term of patent 14 years

(Cl. D33—7)

Fig. 4.

Fig. 6.

Fig. 5.

FIG. 1 is a front perspective view of a work desk for a telephone operator embodying my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a side elevational view thereof.

I claim:

The ornamental design for a work desk for a telephone operator, substantially as shown.
